UNITED STATES PATENT OFFICE

2,415,211

IMAGE PROJECTION SYSTEM

Russell R. Law, Princeton Township, Mercer County, N. J., assignor to Radio Corporation of America, a corporation of Delaware

Application February 19, 1943, Serial No. 476,411

6 Claims. (Cl. 88—24)

1

The present invention relates to an image forming or projection system, and more particularly to a novel optical train giving improved refractive and light transmission effects.

The invention is disclosed herein as being embodied in a system for projecting television pictures or the like, in which the optical system is of the type comprising a spherical mirror and a spherical-aberration correcting plate. As explained in Patent No. 2,273,801, granted to Daniel O. Landis, February 17, 1942, it has been found that a large television picture can be projected with sufficient illumination and with good definition by employing a specially designed optical system of the above mentioned type. When the present invention is employed in conjunction with the projection system disclosed and claimed in the Landis patent, improved results will be obtained as will hereinafter appear.

It is an object of the present invention to provide a novel and improved optical system of the type employing a spherical mirror in which the optical efficiency of the system is greatly enhanced.

The present invention is concerned with changing the refraction of light at the boundary between two media by selecting the contacting media in view of optical properties such as their respective indices of refraction. One of the media must maintain its configuration at the contacting boundary, and therefore a transparent solid is employed. The remaining medium is, in accordance with the present invention, a fluid such as a transparent liquid or a transparent semi-solid, such as a jell. Moreover, in accordance with the invention, immersion of the effective refracting surface of the solid medium may be extended to embrace other elements of the optical train or system, and may for certain applications be carried to the point of total immersion of all of the effective optical elements of the system. In the instance last described the medium selected will preferably be a liquid, and in its selection other properties may be considered, such as its heat conductivity, so as it may serve as a coolant, its dielectric strength, so that it may serve as an electrical insulator, and its density, so that it may provide X-ray shielding.

If the correcting plate is immersed in a transparent medium of suitable index of refraction, the curvatures and variations in thickness of the correcting plate must be greatly exaggerated to give the same optical effect that would be obtained with the unimmersed correcting plate. Conversely, by making a suitable choice of dif-

2

ference of index of refraction between the correcting plate and the liquid, the figure, curvatures or variations in thickness might be exaggerated to any desired degree.

Accordingly, another important object of the present invention is to exaggerate the curvature of a spherical-aberration correcting lens, whereby the requirements on precision of figuring the correcting lens are less stringent.

Still another object of the invention is to make easier the problem of molding a correcting plate from a transparent plastic.

A further object of the present invention is to provide a projection system having a greatly enhanced light efficiency.

A still further object of the invention is substantially to eliminate the effect of halation, making possible improved contrast in an image projected by the optical system.

A still further object of the invention is to effect a reduction in the throw distance of a projection system, and more particularly a television image projection system.

A still further object of the invention is to provide protection for the principal reflecting surface of an optical system employed in projecting images, and more particularly in a television image projection system.

A still further object of the present invention is to provide for more effective electrical insulation and cooling of a television picture reproducing device such as a cathode ray tube and to provide shielding from radiations emanating from such a tube when operated at high voltages, these results being attainable in accordance with the invention separately or together.

The invention will be better understood from the following description taken in connection with the accompanying drawings in which:

Figs. 1 to 3 are diagrams which are referred to in describing principles of the invention existing in an optical system embodying the invention;

Fig. 4 is a side view of a television projection system embodying the invention in modified form, and

Figs. 5 and 6 are views similar to Fig. 4, illustrating other modifications of the invention.

Fig. 7 is a diagram illustrating the gain in light efficiency in accordance with the invention.

Referring to Fig. 1, there is illustrated an optical system of general application embodying the invention. This illustrative system comprises a spherical mirror 10 and a correcting plate 11. The face 12 of the correcting plate is formed or figured to bring light rays from all points of the

mirror into focus at a projection screen 14, which is shown merely in relative location rather than at its optimum spacing from the optical system.

It is assumed that there is a light source 16, such as a cathode ray tube, for instance, at the point indicated. This point may be at the principal focus of the curved mirror, but it is usually between the center of curvature, indicated at 21, and the principal focus when an optical system embodying the invention is to be used for projection work. The principal focal point is halfway between the mirror and its center of curvature 21. Light rays from the source 16 reflected from the mirror 18 near its edge have their focus at a point marked "normal edge focus" in the absence of the correcting plate 11. The path of these rays after leaving the correcting plate is indicated by the dashed line 18. The correcting plate 11 in conjunction with the optical medium 19 is figured within comparatively liberal tolerance limits provided by the invention to refract these rays just enough to make them focus on the projecting screen 14. The correcting plate, it will be understood, is figured so as to make all of the rays originating from the source 16 and reflected from the mirror come to a focus on the screen 14. The solid line 23 indicates the corrected ray path corresponding to the uncorrected ray path 18.

The way in which the tolerance limits are made less stringent by immersing the correcting plate as taught by this invention is clearly illustrated by the following examples.

Referring now to Fig. 2, there is shown, in a conventional manner, a pencil or ray 25 traveling in a transparent medium, for example, glass 26 having an index of refraction of 1.5. The boundary 27 of the glass 26 which is in contact with air makes an angle indicated by 28 with respect to a line 29 drawn so as to be normal to the ray 25. The ray 25 is bent so that it follows the path 31 after emerging from the glass 26. The angle through which the ray is refracted is indicated by reference character 32.

Fig. 3 shows a ray 34 through transparent glass 26 having the same index of refraction as the glass 26 of Fig. 2. The surface of the glass 26 is in contact with a transparent medium 35 such as glycerin which has a lower index of refraction than glass, namely 1.4729. The ray 34, as it emerges from the first medium into the second medium, is to be bent or refracted through the angle 32, which is the same as the angle 32 of Fig. 2, and is so indicated in Fig. 3. The emerging ray 36 of Fig. 3 is to pass through a point 37 corresponding to an identically located point 37 in Fig. 2. In order to fulfill this condition it will be found that the boundary 39 between the media 26 and 35 must make an angle 41 with respect to a line 42 drawn so as to be normal to the ray 34. It will be seen from this brief study of Figs. 1 and 2 that if the angle 28 of Fig. 2 is unchanged, the angle 32 will be decreased with the surface 27 of the glass 26 immersed in a liquid such as the liquid 35.

Referring again to Fig. 1 of the drawings, it will be seen, in view of Figs. 2 and 3, that if the ray indicated by the solid line 23 is to intersect the axis in the plane of the screen 14, the curvature of the correcting plate 11 is exaggerated when the medium 19 is in interfacial contact with the surface 12 of the correcting plate 11. By making a suitable choice of difference in index of refraction between the correcting plate 11 and the immersion medium, the curvature of this correcting

plate may be exaggerated to any desired degree. Inasmuch as the overall optical effect is the same with or without the immersion medium the precision of figuring the correcting plate may be greatly reduced. For example, whereas the conventional arrangement may require that the correcting plate be figured to an accuracy of 0.0001 inch, if the curvature and variations in thickness are exaggerated ten-fold by the immersion principle, which is employed in a novel manner in the present invention, the correcting plate need only be figured to an accuracy of 0.001 inch to give the same performance.

The optical medium 19 may be a liquid or a viscous colloidal suspension and is maintained in facial contact with the surface 12 by a transparent plate 46 which is secured in any suitable manner to the plate 11 along its edge 46, for example, by cement which is not soluble in the liquid transparent medium 19 or the liquid component of the jell.

The lens 11 may be formed from a plastic by molding or casting, since the precision of figuring this lens or correcting plate is greatly reduced by employing the present invention as pointed out above. As specific examples of the ray correcting combination 11 and 19, "Lucite" (methyl methacrylate) having an index of refraction approximately 1.52 to 1.53 was used in conjunction with glycerin or Russian mineral oil as the fluid medium. Another suitable liquid medium is a product obtainable on the market under the name "Texaco Capella AA." These liquids which are mentioned by way of example may also be employed when the correcting plate 11 is formed of polystyrene. The molding of correcting plates from any of the known transparent plastics to an accuracy of 0.0001 inch such as would be required for a conventional spherical mirror and correcting plate arrangement is exceedingly difficult, whereas with an accuracy 0.001 inch such as would be required in a system in which the face 12 of the correcting plate is immersed as described above permits the employment of conventional molding technique.

The point 16 may be on the end 48 of a cathode ray tube (not shown) upon which a television picture appears. When the tube is active numerous light points, in addition to the point 16, will be effective to illuminate the screen 14, and it will be understood that configuration of the tube end 48 and the dimensions, aperture, and the figured surface 12 of the correcting plate will be selected in view of considerations set forth in detail in the Landis patent above referred to, and in a patent to E. G. Ramberg, No. 2,298,808, granted October 13, 1942.

It will be understood that the principles disclosed above in connection with Fig. 1 of the drawings may be applied in terrestrial and astronomical telescopes, cameras and image projectors generally. The location of the elements in the optical system for each case will be governed by well known considerations. For example, in an astronomical telescope, a curved photographic plate will be placed at the focus of the system in Fig. 1 as the focal surface will be curved.

Fig. 4 of the drawings shows a television projection system embodying the invention in which the entire optical system, with the exception of the viewing screen, is immersed in an optical medium 52, such as a liquid or jell selected in view of considerations pointed out above. In addition to having an index of refraction which is less than the index of refraction of the correcting

plate 53, the fluid constituting the optical medium 52 is preferably selected in view of other properties pointed out above, namely its heat conductivity, its dielectric strength, and its density. A spherical mirror 54 is positioned so that it receives light from the active end 55 of the cathode ray tube 51. A fluid tight casing 66 retains the fluid optical medium 52. Suitable supports, such as rings 57, are positioned within the casing 66 with the rings spaced apart sufficiently to provide a groove in which the edge of the mirror 54 is seated. A flange 58 provides a recess in which the edge of the correcting plate 53 is seated and an opening in the center of the correcting plate receives the elongated portion of the cathode ray tube 51. This may be accomplished by using a cement insoluble in or impervious to medium 52.

The casing 66 is provided with brackets or flanges 62 so that it may be secured as a compact optical unit to a support of any desired type such as the interior of a cabinet. The figured surface 63 of the correcting plate 53 is immersed as well as the active end of the cathode ray tube 51 and the mirror 54. A screen 66 is spaced from the mirror 54 at a distance depending upon the optical design of the optical system, including the mirror 54 and the correcting plate 53.

The placement distance of the screen 66 with respect to the mirror 54 is an important feature of the invention in the form disclosed in Fig. 4 of the drawings. Light from the tube end 55 traverses the medium 52 before emerging into the air after passing through the correcting plate 53 and travels in air from the correcting plate 53 to the screen 66. The screen 66 may be placed closer to the mirror 54 since the throw distance is reduced. This result is attained because the principal rays from the mirror 54 form a cone, the axis of which is substantially normal to the boundary between the correcting plate 53 and the air. This effect corresponds to the effect observed when an image is viewed normally to the boundary between two media such as water and air. When the object is in water, for example, and is viewed from the air in this manner, there is no lateral displacement of the object but an apparent change in distance of the object from the observer, the object appearing to be closer. Approximately a 33% reduction in throw distance is attained.

There is also realized substantially twofold gain in light efficiency when the reflective surface 54 of the mirror and the tube end 55 are immersed. This gain in light efficiency comes about because the oblique rays leaving the tube face are not refracted away from the normal when the index of refraction of the immersion fluid matches that of the tube face, and as a consequence, more of them are collected by a mirror of a given size. This is illustrated in Fig. 7 of the drawings in which a segment of the tube end 55 is shown. P indicates a luminous point. Only the smaller cone 56¹ of light rays leaving the point P actually gets picked up at the mirror 54 when it is not immersed, while the light from the large cone 57¹ is picked up when the tube face and the mirror are immersed.

This change in the critical angle of reflection also eliminates the effect of halation, making possible improved contrast in the image appearing on the screen 66.

The surface of the mirror 54 is protected from dust, dirt, corrosive effects of aqueous moisture and other deleterious substances which cause

corrosion or disintegration of the silvering or the finely polished surface of the silver or the polished glass surface.

The liquid medium 52 may serve as a coolant for so much of the tube 51 as is immersed therein. This cooling effect may be enhanced by providing a radiator having suitable conduit connections to the casing 66 so that heat absorbed by the optical medium may be radiated to the air. A circulating means may be provided for circulating medium through the radiator, and a fan or other arrangement may be used for causing motion of air in the neighborhood of the radiator in a well known manner.

As pointed out above, the medium of 52 may be selected for its X-ray absorbent properties so as to provide a measure of protection against hard rays emitted from the cathode ray tube 51. The cathode ray tube will usually be of the type employing higher than normal operating voltages, so as to attain a brilliant image at the end of the tube 55, and these high voltages which frequently are in excess of fifty to seventy kilovolts tend to give rise to X-ray radiation from the impacted target area.

Fig. 5 of the drawings illustrates a modification of the arrangement shown in Fig. 4 in which all of the elements of the optical system, including one face of the viewing screen 70, are immersed in a liquid optical medium 71 selected in view of the considerations mentioned above governing the selection of the medium 52 indicated in Fig. 4 of the drawings. Reference character 72 indicates a cathode ray tube which may be similar to the tube 51 illustrated in Fig. 4 of the drawings. A correcting plate 73 surrounds the neck of the tube in the manner shown in Fig. 4 of the drawings and illustrated more in detail in the two patents referred to above. Any known or desired means may be employed to support the tube 72 and the correcting plate 73 in a housing or container 76, which is filled with the liquid optical medium 71, having an index of refraction lower than the index of refraction of the correcting plate 73. The spherical mirror 77 may be supported at or adjacent to one end of the container 76 by suitable means such as that shown in Fig. 4 of the drawings.

The viewing screen is preferably of translucent material so that the image formed thereon may be viewed externally of the container 76. The arrangement just described possesses the advantage of substantially eliminating chromatic aberration which is present in some degree in the optical system illustrated by Fig. 4 of the drawings. The arrangement disclosed by Fig. 4 of the drawings is in general the preferred modification of the invention. However, where 800 line television pictures, for example, are to be projected the arrangement disclosed in Fig. 5 of the drawings is to be preferred, since with such a high definition, it is desirable to compensate for chromatic aberration even though it involves the sacrifice of the 33% reduction in throw distance attained with the modification of Fig. 4 of the drawings. Tests show that chromatic aberration resulting from the arrangement of Fig. 4 of the drawings are not detrimental to the quality of television pictures reproduced in accordance with present day standards.

The all-immersion arrangement of Fig. 5 of the drawings provides increased insulation for the tube 72 and its electrical connections. The liquid optical medium will then be selected with this property in mind as well as other desirable prop-

erties mentioned above. If the medium is hygroscopic to an appreciable degree, the liquid should be handled before introduction into the container 78 with the precautions usual in handling transformer oil or other liquid insulators for electrical apparatus.

Fig. 6 of the drawings discloses an arrangement wherein chromatic aberration of the entire projection cell or unit, indicated generally by reference character 79, is compensated for in a novel manner. In selecting the liquid optical medium 81, which is contained within the cell 19, the property of dispersion must be considered in conjunction with the dispersive power of a liquid optical medium 82 contained in a screen cell indicated generally by the reference character 83. This screen cell comprises a transparent wall 84 and a translucent wall 86, the latter serving as the viewing screen. These walls are joined together in any suitable manner so as to provide the liquid tight cavity between them, which contains the liquid medium 82. For achromatism the product of the dispersion of the medium 81 in the projection cell 78 and the distance 88 from the projection cell 79 to the screen cell 83 should equal the product of the dispersion of the medium 82 in the screen cell 83 and the thickness 89 of the screen cell. By way of example, the transparent liquid in an embodiment of the invention operated for test purposes was mineral oil and the liquid in the screen cell was carbon disulphide (CS_2).

From the foregoing it will be seen that the invention provides a method of and means for giving a prescribed exaggeration of the figure of a correcting lens or plate useful for general optical purposes. Also, the invention provides a television picture projection system having a television reproduction tube and reflective mirror immersed with a corrective lens in a common medium to form a projection cell. It will be understood in this connection by those skilled in the art that all of the mechanical and optical refinements disclosed in the two patents referred to above may be applied to television projection apparatus embodying the present invention. For example, the arrangement disclosed by Fig. 3 of the Landis patent, including the mirror 19, may be followed in designing a television projector embodying this invention. The invention further provides for use of such a projection cell with a screen cell containing a suitable medium and so proportioned as to provide achromatism.

The nature of the invention will be determined from the foregoing, and the scope thereof is defined in the appended claims.

Having now described the invention, what is claimed and desired to be secured by Letters Patent is the following:

1. An optical system comprising a concave spherical mirror, a correcting plate positioned to transmit light reflected from said spherical mirror, said correcting plate having a figured surface the curvatures of which are exaggerated, and a readily deformable optical medium in interfacial contact with the figured surface of said correcting plate, said optical medium and said correcting plate having indices of refraction differing from each other whereby the correcting plate functions in the same manner as a correcting plate having unexaggerated curvatures in contact with air.

2. An optical system for image projection and enlarging comprising a light source adapted to emit light to produce a bi-dimensional optical

picture image of finite area substantially centered on the optical axis of the system, a light reflecting surface of revolution having its concave surface positioned to reflect the light issuing from said source, an aspherical zone plate positioned to receive the reflected light projected from said light source, said zone plate having a figured surface and being arranged external to the light path from the light source to the reflector and axially aligned with each and adapted to correct the spherical aberrations introduced into the reflected light rays by the reflecting surface, and means for exaggerating the zones of said aspherical zone plate comprising a liquid optical medium immersing the figured surface of said zone plate, means for maintaining the liquid optical medium in contact with the zones of said aspherical zone plate, said zone plate and said liquid optical medium having selected differences of their refractive indices giving the same optical effect as would be obtained with an unimmersed and unexaggerated correcting plate.

3. A projection system comprising a concave spherical mirror, a correcting plate having a figured surface and positioned to receive light reflected from said spherical mirror, a projection tube having an object surface therein which is positioned at a conjugate focus of said system, and a fluid tight enclosure for maintaining a fluid optical medium of selected difference of refractive index in physical contact with said mirror, the figured surface of said correcting plate and the object surface of said tube, to immerse the figured surface of said correcting plate whereby the selected differences of the refractive indices of the plate and immersing medium permit the figured surface of the correcting plate to be greatly exaggerated and which in connection with the said immersing medium gives the same optical effect that would be obtained with an unimmersed correcting plate.

4. A projection system comprising a concave spherical mirror, a correcting plate having an optically active surface positioned to receive and transmit light reflected from said spherical mirror, a projection tube having an object surface therein which is positioned at a conjugate focus of the system, a viewing screen receiving light in the form of a readily perceptible image transmitted by said correcting plate, and a fluid optical medium in which said projection tube, the optically active surface of said correcting plate, said mirror and the light receiving face of said viewing screen are immersed, said fluid optical medium having an index of refraction differing from that of said correcting plate.

5. An optical system comprising a concave spherical mirror, a correcting plate positioned to transmit light received from said spherical mirror, a projection tube having an object surface therein which is positioned at a conjugate focus of the system, a viewing screen spaced from said spherical mirror, a liquid optical medium in the light path from said projection tube object surface to said correcting plate, and a second liquid optical medium in contact with said viewing screen so as to be traversed by light transmitted by said correcting plate for a portion of its path, said first named liquid optical medium having index of refraction differing from that of said correcting plate, said first and second liquid optical media having values of dispersion such that the product of the portion of the light path in linear units along the axis of said system from said correcting plate to said second liquid

optical medium multiplied by the dispersion value of said first named liquid optical medium is equal to the product of the path in linear units traversed by light passing from said correcting plate to said viewing screen through said second fluid optical medium multiplied by the dispersion value of said second named liquid optical medium, whereby said optical system is achromatic.

6. An optical combination comprising a spherical mirror with aberrations and a correcting plate for the aberrations for transmitting directed light in which the refractive effect of the plate is decreased so that tolerance requirements in forming the element may be relaxed, said plate having a figured surface, the curvature of the 15 figured surface being exaggerated, a fluid optical medium in contact with and immersing said figured surface, the fluid optical medium having a different index of refraction so related to the index of refraction of the material of the figured 20

plate that the plate functions in the same manner as an element having an unexaggerated figure will function when immersed in air.
